United States Patent Office

Des. 184,921
Patented Apr. 21, 1959

184,921

AUTOMOBILE

Alvin L. Eggers, Denver, Colo.

Application June 3, 1958, Serial No. 51,171

Term of patent 7 years

(Cl. D14—3)

FIG. 1

I claim:

The ornamental design for an automobile, substantially as shown.
